UNITED STATES PATENT OFFICE.

JOHN L. LIND, OF SIREN, WISCONSIN.

PORTABLE PHONOGRAPH.

Application filed December 5, 1921. Serial No. 519,983.

To all whom it may concern:

Be it known that I, JOHN L. LIND, a citizen of the United States, residing at Siren, in the county of Burnett and State of Wisconsin, have invented certain new and useful Improvements in Portable Phonographs; and I do declare the following to be a full, clear, and exact description of the invention, such as will enable others skilled in the art to which it appertains to make and use the same.

My invention relates to improvements in sound reproducing machines and more particularly to those of the portable type, in which the sound arm, reproducer, and record table are removed and stored within the main cabinet or box of the machine to be readily carried from place to place. The present application forms a continuation in part of my pending U. S. application, Serial No. 397,185, filed July 19, 1920.

One object of the invention is to provide a unique form of case or cabinet containing the horn and motor, provided with a door equipped in one side with means for carrying the record table, tone arm, reproducer, crank, etc., when their use is not necessary, the construction being such that closing of the door will move these parts into the cabinet.

Another aim of the invention is to provide a unique form of carrying handle for the box, which is normally swung to a carrying position above the upper side thereof and located over the driving spindle for the record table, said handle however, being capable of swinging downwardly to one side of the box or cabinet so as to be entirely out of the way when the record table is to be applied to the spindle.

A further object of the invention is to provide for normally closing the discharge end of the horn by a door which can be swung downwardly and then moved into the case beneath the horn.

With the foregoing and minor objects in view, the invention resides in the novel subject matter hereinafter described and claimed, the descriptive matter being supplemented by the accompanying drawings.

Figure 1 is a perspective view of a portable phonograph constructed in accordance with the present invention, showing the manner in which the device resembles an ordinary suit case when in condition for carrying from one place to another.

Figure 2 is a view similar to Fig. 1 but illustrating the instrument in condition for use.

Figure 3 is a side elevation with the door 60 swung open to expose the record table and other parts normally carried in the box or cabinet.

Figure 4 is a horizontal section as indicated by the line 4-4 of Fig. 5. 65

Figure 5 is a longitudinal sectional view.

In the drawings above briefly described, the numeral 1 designates a rectangular cabinet or case of the general shape of an ordinary suit case, one side of said case being provided with an outwardly swinging door 2, while one end of said case is equipped with a door 3 having a pintle 4 slidable in a groove 4^a in one side of the case 1, so that by swinging said door downwardly, it may 75 slide into the box, as in Figs. 2 and 3. A horn 5 is located in the case 1 with its discharge end normally closed by the door 3, said horn being spaced inwardly from the door 2 and having its inner end in communication with an opening 6 formed in the top 7 of the case 1. When the several detachable parts and accessories are being carried within the case, the opening 6 may well be closed by any suitable form of detachable 80 plate 8 as indicated in Fig. 1, but when this plate is removed, a tone arm 9 having a reproducer 10, is applicable to the top 7 of the case 1, in communication with the aforesaid opening. The horn 5 may be of the same cross sectional area as those now 85 commonly used.

The central portion of the top 7 carries a spring motor 12 provided with a spindle 13 rising through said top for driving a record table 14. The usual hand crank 15 90 is provided for winding the motor 12 and this crank, together with the record table 14, the tone arm 9 and the reproducer 10, may all be housed in the case 1 when the instrument is to be carried from one place 95 to another. I preferably provide a box 16 on the inner side of door 2 and movable into the case 1, below the horn 5, to contain the reproducer, the crank and the tone arm.

For holding the record table 14 within the case 1, I preferably provide the construction shown most clearly in Fig. 3. A pair of cleats 17 are secured to the inner side of the door 2 and extend vertically across the same, the lower ends of said cleats being 110 connected by a board 18 to form therewith

a pocket to receive the table 14 when the latter stands on edge against the inner side of the door. The moment the door is swung open, the record table may be easily removed so that it may be quickly applied to the spindle 13, any suitable driving connection being employed between the two. It will be observed that opening of the door 2 not only permits access to the table 14, but allows the crank 15, the tone arm 9 and the reproducer 10 to be conveniently removed from the box 16.

10 A motor control 19 and a release 20 for the latch of door 2 preferably extend 15 through the horn 5 as shown in Figs. 2, 4 and 5.

In order that the case and its contents may be easily carried, I provide a novel form of handle which is normally positioned 20 above the top 7, but may be folded downwardly to an out of the way position when the table 14 is to be applied to the spindle 13. In the present showing, the handle includes a U-shaped spring metal bail 22 25 whose arms 23 are laterally bent in the same direction at 24, between their ends, being provided at their terminals with eyes 25. A leather or other suitable hand grip 26, which may well be an ordinary suit case 30 handle, is connected with the eyes 25. The arm-connecting portion of the bail 22 is pivoted upon the top 7 of the case 1 by appropriate bearings 27 and when the handle is in case-carrying position as seen in Figs. 1 35 and 3, the portions of the arms 23 contiguous to said arm-connecting portion, rest upon said top 7, while the laterally bent arm ends extend upwardly from said top. To hold the bail in this position, oppositely 40 facing hooks or keepers 28 are secured to the top 7 and in order to engage the arms 23 with these keepers, it is necessary to spring said arms outwardly to some extent. When they are once hooked into the keepers, however, and the weight of the entire 45 device is lifted by the hand grip 26, this grip exerts an inward pull on the arms 23 and thereby effectively retains them in the keepers. When the table 14 is to be used, the entire handle is disengaged from the 50 hooks or keepers 28 and swung downwardly to the position seen in Fig. 2, in which position, the lateral ends 24 of the arms 23, and the hand grip 26, lie at one side of the case 1.

From the foregoing, it will be seen that I have provided a very simple and compact arrangement for carrying out the objects of the invention, and since probably the best

results may be obtained from the details disclosed, they are by preference followed. I wish it understood, however, that within the scope of the invention as claimed, numerous minor changes may be made.

I claim:

1. A portable graphophone comprising a casing having an outwardly swinging door occupying the major portion of one of its vertical sides, a horn within the casing spaced inwardly from said door, and means 70 for mounting a record table upon the inner side of said door when it is not in use, whereby to position said record table between said door and horn when the former is closed.

2. A portable graphophone comprising a rectangular case having an outwardly swinging door occupying the major part of one of its sides, a horn within said case spaced from a side thereof adjacent said door, said horn being adapted for communication with a tone arm, and a box carried by the inner side of said door, said box being movable into the case into the space between said horn and the second mentioned 85 side of the case, being adapted to contain the tone arm and other accessories.

3. The combination with a graphophone case, of a U-shaped spring metal bail pivotally mounted upon said base and having 90 its ends connected by a handle, said bail being movable upon its pivotal axis to an inoperative position, and a pair of outwardly facing hooks carried by the top of the case and adapted to engage the arms of said 95 bail to hold the latter in carrying position, the inward pull exerted on the arms of the bail by the handle, serving to retain said arms within said hooks.

4. The combination with a graphophone 100 case, of a U-shaped bail whose arm-connecting portion extends horizontally along the casing top, bearings extending over said arm-connecting portion of the bail and pivoting the latter to the top of the case, the 105 portions of the bail arms adjacent said arm-connecting portion being adapted to normally rest upon the top of said case, the free end portions of said arms being bent upwardly and connected by a handle, and 110 outwardly facing hooks carried by the top of the case and normally engaging the inner portions of the bail arms to hold the latter in carrying position.

In testimony whereof I have hereunto 115 set my hand.

JOHN L. LIND.
